SELECTIVE HYDROGENATION OF TRI- AND TETRAZOLOISOQUINOLINES

Ernest H. de Ruiter, Beersel, and Hans K. Reimlinger, Brussels, Belgium, assignors to Mallinckrodt Chemical Works, St. Louis, Mo.

No Drawing. Continuation of abandoned application Ser. No. 743,624, July 10, 1968. This application Aug. 5, 1971, Ser. No. 169,521

Int. Cl. C07d 55/06

U.S. Cl. 260—288 R

1 Claim

ABSTRACT OF THE DISCLOSURE

Tri- and tetrazoloisoquinolines, such as 3-amino-s-triazolo[3,4-a]isoquinoline or 5 - methylthiotetrazolo[5,1-a]isoquinoline, are selectively hydrogenated in the 5,6 position at a temperature within the range of from about 50° to about 160° C. provided that the temperature selected is not more than about 50° C. higher than the temperature at which hydrogenation is first observed, in the presence of a catalytic quantity of a nickel, platinum, or palladium hydrogenation catalyst, for a period of time and at a pressure sufficient to hydrogenate the 5,6 position.

The invention relates to a process for selectively hydrogenating tri- and tetrazoloisoquinolines in the 5,6 position. More particularly, the process comprises contacting a tri- or tetrazoloisoquinoline with hydrogen in the presence of a nickel, palladium, or platinum catalyst under carefully controlled conditions, which is described herein below.

The tri- and tetrazoloisoquinolines that are selectively hydrogenated by the process of the invention are illustrated by the following three classes of compounds:

s-Triazolo[5,1-a]isoquinolines, that have the following basic structure:

(I)

Tetrazolo[5,1-a]isoquinolines that have the following basic structure:

(II)

s-Triazolo[3,4-a]isoquinolines which have the following basic structure:

(III)

In the foregoing formulas, the variables R⁵, R⁶, R⁷, R⁸, R⁹ and R¹⁰ individually can represent substituents such as hydrogen, alkyl, cycloalkyl, aryl, halo, amino, dialkyl-

2

amino, aminoalkylamino, dialkylaminoalkylamino, dialkylaminoalkoxy, hydroxy, sulfhydryl, alkylthio, cyano, haloalkyl, aminoalkyl, and the like, Preferred R⁵ through R¹⁰ variables include hydrogen, bromo, chloro, lower alkoxy and lower alkyl (i.e., C₁—C₄ alkyl and alkoxy) especially methoxy, methyl, and ethyl, lower alkylthio especially methylthio, cyano, amino, dimethylamino, diethylamino, 2-aminoethylamino, 3-aminopropylamino, 2-dimethylaminoethylamino, 3-dimethylaminopropylamino, 2-dimethylaminoethoxy, aminoethyl, and the like. Usually the R⁵ through R¹⁰ substituent group will contain not more than 20 carbon atoms, and preferably not more than 8 carbon atoms. The R² variable can represent alkyl, alkaryl, aralkyl, aryl, amino, haloalkyl, cycloalkyl, heterocyclic groups (particularly 5- or 6-membered rings containing oxygen or nitrogen as the hetero atom), and alkoxyalkyl. Usually, R² will contain not more than 20, and preferably not more than 10, carbon atoms. Preferred R² variables are lower alkyl (i.e., C₁—C₄ alkyl) and especially methyl, trifluoromethyl, and phenyl. The R³ variable can be hydrogen, amino, or aliphatic, aromatic, cycloaliphatic, or heterocyclic groups containing up to 24 carbon atoms.

The hydrogenated products are compounds that can be represented by the formulas:

(I-h)

(II-h)

(III-h)

55 wherein the several R variables have the significance stated above with respect to Formulas I, II and III.

The s-triazolo[3,4-a]isoquinolines can be produced by reacting a 1-hydrazinoisoquinoline with an acidic reagent such as an acyl halide, a carboxylic acid anhydride, an orthoformic ester, a carboxylic acid, carbon disulfide, cyanogen bromide, an isocyanate, or a urethane. Descriptions of processes for producing s-triazolo[3,4-a]isoquinolines are found in copending application Ser. No. 634,077, filed Apr. 27, 1967 for "s-Triazolo[3,4-a]Isoquinolines and Derivatives Thereof" by H. Reimlinger et al. (assigned to the same assignee as this application, now abandoned); in U.S. Patent No. 3,354,164; in an article by Naqui et al., Indian Journal of Chemistry 3, 162 (1965); and in an article by Sidhu et al., Journal of Heterocyclic Chemistry 3, 158-164 (1966).

Illustrative s-triazolo[3,4-a]isoquinolines that can be used in the invention include, among others,

3-amino-s-triazolo[3,4-a]isoquinoline,
 3-aminoethyl-s-triazolo[3,4-a]isoquinoline,
 3-aminoethyl-s-triazolo[3,4-a]isoquinoline,
 3-(N,N-dimethylaminomethyl)-s-triazolo[3,4-a]isoquinoline,
 3-(N-methylaminomethyl)-s-triazolo[3,4-a]isoquinoline,
 3-(N,N-diethylaminopropyl)-s-triazolo[3,4-a]isoquinoline
 3-(N,N-dimethylaminomethyl)-s-triazolo[3,4-a]isoquinoline,
 3-(N,N-dimethylaminomethyl)-s-triazolo[3,4-a]isoquinoline,
 3-(N,N-dimethylaminopropyl)-s-triazolo[3,4-a]isoquinoline,
 3-trifluoromethyl-s-triazolo[3,4-a]isoquinoline,
 3-chloroethyl-s-triazolo[3,4-a]isoquinoline,
 3-hydroxyalkyl-s-triazolo[3,4-a]isoquinoline,
 3-carboethoxy-s-triazolo[3,4-a]isoquinoline,
 3-carboethoxymethyl-s-triazolo[3,4-a]isoquinoline,
 3-(N-methylcarbamido)-s-triazolo[3,4-a]isoquinoline,
 3-(N-methylamidomethyl)-s-triazolo[3,4-a]isoquinoline,
 3-(N-ethylamidomethyl)-s-triazolo[3,4-a]isoquinoline,
 3-(N,N-dimethylamidomethyl)-s-triazolo[3,4-a]isoquinoline,
 3-hydroxy-5-methyl-s-triazolo[3,4-a]isoquinoline,
 3,5-dimethyl-s-triazolo[3,4-a]isoquinoline,
 5-methyl-s-triazolo[3,4-a]isoquinoline,
 3-carboethoxy-5-chloro-s-triazolo[3,4-a]isoquinoline,
 5-chloro-s-triazolo[3,4-a]isoquinoline,
 3-benzylamidomethyl-5-chloro-s-triazolo[3,4-a]isoquinoline,
 3-carboethoxymethyl-5-chloro-s-triazolo[3,4-a]isoquinoline,
 5-methoxy-s-triazolo[3,4-a]isoquinoline,
 3-benzylamido-5-benzylamino-s-triazolo[3,4-a]isoquinoline,
 5-(N-piperidyl)-s-triazolo[3,4-a]isoquinoline,
 3-methyl-6-chloro-s-triazolo[3,4-a]isoquinoline,
 3-trifluoromethyl-6-chloro-s-triazolo[3,4-a]isoquinoline,
 3-methylthio-6-chloro-s-triazolo[3,4-a]isoquinoline,
 6-chloro-3-carboethoxymethyl-s-triazolo[3,4-a]isoquinoline,
 3-thio-6-chloro-s-triazolo[3,4-a]isoquinoline,
 3-ethylthio-6-chloro-s-triazolo[3,4-a]isoquinoline,
 3-benzoylaminomethyl-6-chloro-s-triazolo[3,4-a]isoquinoline,
 3-(α -aminoethyl)-6-chloro-s-triazolo[3,4-a]isoquinoline,
 3-(α -aminopropyl)-6-chloro-s-triazolo[3,4-a]isoquinoline,
 3-benzylcarbamidoethyl-6-chloro-s-triazolo[3,4-a]isoquinoline,
 3-(1-benzylcarbamido-2-methylethyl)-6-chloro-s-triazolo[3,4-a]isoquinoline,
 6-chloro-s-triazolo[3,4-a]isoquinoline,
 6-bromo-s-triazolo[3,4-a]isoquinoline,
 6-methyl-s-triazolo[3,4-a]isoquinoline,
 6-cyano-s-triazolo[3,4-a]isoquinoline,
 3-trifluoromethyl-6-cyano-s-triazolo[3,4-a]isoquinoline,
 6-nitro-s-triazolo[3,4-a]isoquinoline,
 6-amido-s-triazolo[3,4-a]isoquinoline,
 3-carbomethoxy-6-chloro-s-triazolo[3,4-a]isoquinoline,
 8,9-dimethoxy-s-triazolo[3,4-a]isoquinoline,
 3-trifluoromethyl-8,9-dimethoxy-s-triazolo[3,4-a]isoquinoline,
 6-chloro-8,9-dimethoxy-s-triazolo[3,4-a]isoquinoline,
 3-trifluoromethyl-6-chloro-8,9-dimethoxy-s-triazolo[3,4-a]isoquinoline,
 7-nitro-s-triazolo[3,4-a]isoquinoline,
 7-amino-s-triazolo[3,4-a]isoquinoline hydrochloride,
 7-nitro-6-hydroxy-s-triazolo[3,4-a]isoquinoline,

and the like.

The s-triazolo[5,1-a]isoquinolines can be produced by the following sequence of reactions, starting with known types of reactants:

(a) A 1-aminoisoquinoline is reacted with a nitrile to produce an N-(1-isoquinolyl)amidine:

(b) The N-(1-isoquinolyl)amidine is then contacted with lead tetraacetate to effect ring closure and thereby produce the s-triazolo[5,1-a]isoquinoline:

Reaction (a) is carried out by reacting a 1-aminoisoquinoline with a nitrile. Ordinarily, a Lewis acid catalyst is used, although in some cases, no catalyst is needed.

The nitriles that are used are compounds of the formula:

(1) R²CN

where R² represents alkyl, alkaryl, aralkyl, aryl, haloalkyl, cycloalkyl, heterocyclic groups, alkoxyalkyl groups, and the like.

Specific illustrative nitriles that can be used in the invention include the following compounds:

acetonitrile,	decanenitrile,
propionitrile,	dodecanenitrile,
35 butyronitrile,	tetradecanenitrile,
valeronitrile,	hexadecanenitrile,
hexanenitrile,	octadecanenitrile,
heptanenitrile,	eicosanenitrile,
octanenitrile,	

and other alkanenitriles having up to 20 carbon atoms. The preferred alkanenitriles are those having up to six carbon atoms, and those having from two to four carbon atoms are more preferred.

Other useful nitriles include the aromatic and cycloalkyl nitriles such as the following compounds:

benzonitrile,
 cyclohexanenitrile,
 cyclopentanenitrile,
 50 p-methylbenzonitrile,
 phenylacetonitrile (benzyl cyanide),
 α -phenylbutyronitrile,
 and the like.

Other useful nitriles include the haloalkyl nitriles such as the following compounds:

60	chloroacetonitrile, trichloroacetonitrile, trifluoroacetonitrile, fluoroacetonitrile, β -chloropropionitrile, β -bromopropionitrile, γ -chlorobutyronitrile, α -chloroisobutyronitrile,

and the like.

Still other useful nitriles include the heterocyclic nitriles such as the following compounds:

70	α -cyanotetrahydrofuran 2-furylacetonitrile, 2-cyanopyridine, N-(β -cyanoethyl)pyrrole,

and the like.

Other useful nitriles include methoxyacetonitrile, β -methoxypropionitrile, ethoxyacetonitrile, and the like.

The nitriles that are employed in the invention are a well known class of compounds that can be obtained by known procedures. Nitriles are readily prepared, for instance, by reaction of benzyl chlorides or primary or secondary alkyl chlorides with alkali metal cyanide, by reaction of potassium arylsulfonic acid salts with potassium cyanide, by the dehydration of an amide, by dehydration of oximes, or by other known procedures.

In reaction (a), the other starting reactant is a 1-aminoisoquinoline. These compounds can be obtained by the following types of reactions:

(c) The known reaction of unsubstituted isoquinoline or hydrocarbyl-substituted isoquinolines with sodium amide in liquid ammonia:

(d) The known reaction of 1,3-dichloroisoquinolines with alcoholic ammonia at 180° C.:

(e) The known reduction of a 1-hydrazinoisoquinoline (prepared by reacting a 1-chloroisoquinoline with hydrazine) with hydrogen using a palladium catalyst:

(in the published cases, R was ethyl or butyl, but it can be other alkyl, aryl, or the like).

(f) Reaction of a 1-methoxyisoquinoline with sodium amide and liquid ammonia at atmospheric pressure in refluxing toluene:

1-methoxyisoquinolines are produced by refluxing 1-chloroisoquinolines with sodium methoxide in methanol. Under these conditions, chloro substituents on the 4 position do not react. By this procedure, 1-amino-4-chloroisoquinolines can be produced.

(g) 1-amino-4-nitroisoquinolines can be prepared by the conventional nitration of a 1-aminoisoquinoline. The nitro group does not interfere with reactions (a) and (b), and it can be used subsequently for producing derivatives of s-triazolo[5,1-a]isoquinolines having substituents in the 6 position. The nitration reaction is exemplified by the following:

(h) 1-aminoisoquinolines having alkoxy substituents in the benzene ring or other easily reducible substituents can be produced by the following sequence of reactions:

The foregoing techniques can be used to prepare a wide variety of 1-aminoisoquinolines. Unsubstituted and hydrocarbyl-substituted 1-aminoisoquinolines are readily available via reaction (c). 1-aminoisoquinolines containing chloro substituents are readily available via reactions (d) or (f). 1-amino-4-nitroisoquinolines can be produced by reaction (g). 1-aminoisoquinolines containing alkoxy substituents are available through the corresponding 1-hydrazinoisoquinolines by reactions (e) and (h). The corresponding 1-hydrazinoisoquinolines are readily prepared by the known reaction of a 1-chloroisoquinoline with hydrazine. Many 1-chloroisoquinolines are known. A useful method for synthesizing 1-chloroisoquinolines is to react an isocarbostyryl with phosphorus oxychloride in accordance with the following reaction:

In preparing a 1-hydrazinoisoquinoline from a 1-chloroisoquinoline that contains additional chloro substituents, the reaction with hydrazine should be carried out in methanol. The 1-hydrazinoisoquinoline is formed first, and it then precipitates from solution thereby avoiding the preparation of poly-hydrazinoisoquinolines.

Among the 1-aminoisoquinolines that can be used in reaction (a) are the following compounds:

- 55 1-aminoisoquinoline,
- 1-amino-3-chloroisoquinoline,
- 1-amino-4-chloroisoquinoline,
- 1-amino-3-methylisoquinoline,
- 1-amino-3-methyl-4-cyanoisoquinoline,
- 60 1-amino-4-ethoxyisoquinoline,
- 1-amino-4-butoxyisoquinoline,
- 1-amino-4-nitroisoquinoline,
- 1-amino-6,7-dimethoxyisoquinoline,
- 1-amino-5,6,7-trimethoxyisoquinoline,
- 65 1-amino-7-methoxyisoquinoline,
- 1-amino-6-methoxyisoquinoline,
- 1-amino-3-ethylisoquinoline,
- 1-amino-5-methoxyisoquinoline,
- 1-amino-7-chloroisoquinoline,
- 70 1-amino-3-phenylisoquinoline,
- 1-amino-3-phenyl-4-chloroisoquinoline,

and the like.

The preferred 1-aminoisoquinolines are unsubstituted 1-aminoisoquinoline and derivatives thereof containing alkoxy, alkyl, chloro, and nitro substituents.

Reaction (a) is carried out by reacting a 1-aminoisoquinoline with nitrile. In most cases, a Lewis acid catalyst is required for the reaction, although with some nitriles containing fluoro substituents on the alpha carbon atom, no catalyst is needed. The Lewis acid catalysts used are compounds such as aluminum trichloride, titanium tetrachloride, tetrakisopropyl titanate, boron trifluoride, and the like. Aluminum trichloride is preferred. The catalyst is employed in catalytically effective quantities, such as from about 10 to 150 weight percent, and preferably from about 50 to 120 weight percent, based upon weight of the 1-aminoisoquinoline.

With some nitriles having one or more fluoro substituents on the alpha carbon atom, no catalyst is needed. For instance, when trifluoroacetonitrile is used in reaction (a), no catalyst is required.

The exact temperature to be used in the reaction depends in part, upon the nature of the reactants, and particularly upon the nature of the nitrile. For instance, when trifluoroacetonitrile is used in reaction (a), the reaction proceeds at room temperature. With less reactive nitriles, higher temperatures are used. For instance, temperatures of from about 150° C. to about 210° C can be used, with temperatures of from about 175° to about 200° C. being preferred.

The reaction is conveniently carried out in an inert solvent either by adding catalyst to a solution of nitrile plus 1-aminoisoquinoline, or by adding nitrile to a solution of 1-aminoisoquinoline (either with or without a catalyst). In any event, it is desirable to avoid adding nitrile to catalyst without a 1-aminoisoquinoline being present in order to avoid trimerization of the nitrile to an s-triazine which will reduce the yields of the desired amidine product of reaction (a).

Suitable inert solvents include hydrocarbons such as benzene, toluene, xylene, naphthalene, methylnaphthalene, and the like.

The proportions of the reactants are not narrowly critical. About stoichiometric proportions can be used, although higher yields are obtained in most cases when excess nitrile is employed. It is therefore desirable to employ up to about 150 percent molar excess of nitrile.

The reaction can be carried out in conventional equipment at atmospheric pressure, or under super-atmospheric pressure in the event that the reaction is to be carried out at a temperature exceeding the boiling point of any of the reactants or solvent. In such cases, the reaction is preferably carried out in a closed vessel under autogenous pressure.

Reaction (a) is carried out for a period of time sufficient to produce an N-(1-isoquinolyl)amidine. The exact time selected will vary, to an extent, with the reaction temperature and the nature of the amidine. Usually, the higher temperature reactions are faster, for instance, from about 1/2 to about 5 hours, and preferably from about 2 to about 3 hours. The reactions that are carried out at low temperatures, e.g., those wherein the nitrile is activated by fluoro substituents on the alpha carbon atom, normally are slower. For instance, reaction times of up to 100 hours, and preferably from about 25 to about 80 hours, can be employed.

The amidine product is recovered by conventional procedures. For instance, the reaction mixture containing catalyst, product, and unreacted starting material can be poured into aqueous acid (such as hydrochloric acid) to form a water-soluble amidine salt. The solvent can then be decanted, after which the aqueous mixture can be cooled and alkali added to precipitate the organic materials (i.e., product and unreacted starting material). The crude amidine can then be purified by dissolving it in diethyl ether, drying the ethereal solution, and evaporating the ether. The amidine can be further purified by dissolving it in benzene and passing the benzene solution through a neutral aluminum oxide column. The unreacted starting ma-

terial is adsorbed in the column, and the pure amidine is recovered by evaporating the benzene.

In cases where no Lewis acid catalyst is used, it is not necessary to use water extraction. In many cases, the amidine can be recovered simply by evaporating the solvent. In some cases, it may also be desirable to pass a solution of the amidine through a neutral aluminum oxide column in order to remove unreacted starting material.

In the second step for producing the s-triazolo[5,1-a]isoquinolines of the invention, i.e., reaction (b), the amidine product of reaction (a) is contacted with lead tetraacetate to effect ring closure and thereby produce an s-triazolo[5,1-a]isoquinoline. This reaction is carried out simply by heating a mixture of the amidine and lead tetraacetate in a suitable solvent for a period of time sufficient to effect ring closure. The temperature can vary from about 75° C. to about 125° C. The reaction time will vary depending on the temperature, nature of the amidine, and the like, but in general will be from about 10 minutes to about 45 minutes.

A convenient way to carry out reaction (b) is to reflux a mixture of amidine and dry lead tetraacetate in a solvent having a suitable boiling point. Such solvents include benzene, toluene, xylene, cyclohexane, glacial acetic acid, or mixtures thereof.

The lead tetraacetate is preferably used in at least stoichiometric proportions. For instance, from about 1.1 to about 2 moles of lead tetraacetate per mole of amidine is suitable in most cases.

The s-triazolo[5,1-a]isoquinoline product of reaction (b) can be recovered by conventional procedures. For instance, the cooled reaction mixture can be washed with aqueous alkali, and the product can be separated from the basic aqueous mixture as a solution in a hydrocarbon solvent such as benzene. After drying, the solvent can be removed by evaporation to yield the product. Further purification by recrystallization can be performed if desired.

Among the s-triazolo[5,1-a]isoquinolines that can be produced, by the sequence of reactions (a) and (b) described above, from known and/or readily available nitriles and 1-aminoisoquinolines, are the following specific illustrative compounds:

2-methyl-s-triazolo[5,1-a]isoquinoline,
2-ethyl-s-triazolo[5,1-a]isoquinoline,
2-propyl-s-triazolo[5,1-a]isoquinoline,
2-butyl-s-triazolo[5,1-a]isoquinoline,
2-pentyl-s-triazolo[5,1-a]isoquinoline,
5-chloro-2-methyl-s-triazolo[5,1-a]isoquinoline,
6-chloro-2-methyl-s-triazolo[5,1-a]isoquinoline,
2,5-dimethyl-s-triazolo[5,1-a]isoquinoline,
2,5-dimethyl-6-cyano-s-triazolo[5,1-a]isoquinoline,
9-chloro-2-methyl-s-triazolo[5,1-a]isoquinoline,
2-ethyl-6-nitro-s-triazolo[5,1-a]isoquinoline,
6-ethoxy-2-methyl-s-triazolo[5,1-a]isoquinoline,
6-butoxy-2-hexyl-s-triazolo[5,1-a]isoquinoline,
7-methoxy-2-methyl-s-triazolo[5,1-a]isoquinoline,
8-methoxy-2-methyl-s-triazolo[5,1-a]isoquinoline,
9-methoxy-2-methyl-s-triazolo[5,1-a]isoquinoline,
8,9-dimethoxy-2-methyl-s-triazolo[5,1-a]isoquinoline,
7,8,9-trimethoxy-2-methyl-s-triazolo[5,1-a]isoquinoline,
and other 2-alkyl-s-triazolo[5,1-a]isoquinolines.

Other illustrative compounds include:

2-phenyl-s-triazolo[5,1-a]isoquinoline,
2-cyclohexyl-s-triazolo[5,1-a]isoquinoline,
2-cyclopentyl-s-triazolo[5,1-a]isoquinoline,
2-tolyl-s-triazolo[5,1-a]isoquinoline,
2-phenylmethyl-s-triazolo[5,1-a]isoquinoline,
5-chloro-2-phenyl-s-triazolo[5,1-a]isoquinoline,
6-chloro-2-phenyl-s-triazolo[5,1-a]isoquinoline,
8-methoxy-2-phenyl-s-triazolo[5,1-a]isoquinoline,
and other 2-aryl-, 2-cycloalkyl-, 2-alkaryl-, and 2-alkyl-s-triazolo[5,1-a]isoquinolines.

Additional specific illustrative compounds include:

2-trifluoromethyl-s-triazolo[5,1-a]isoquinoline,
2-chloromethyl-s-triazolo[5,1-a]isoquinoline,
2-trichloromethyl-s-triazolo[5,1-a]isoquinoline,
2-fluoromethyl-s-triazolo[5,1-a]isoquinoline,
2-(beta-chloroethyl)-s-triazolo[5,1-a]isoquinoline,
2-(gamma-chloropropyl)-s-triazolo[5,1-a]isoquinoline,
7,8,9-trimethoxy-2-trifluoromethyl-s-triazolo[5,1-a]isoquinoline,
6-nitro-2-trifluoromethyl-s-triazolo[5,1-a]isoquinoline,
and other 2-haloalkyl-s-triazolo[5,1-a]isoquinolines.

Further illustrative compounds include:

2-methoxymethyl-s-triazolo[5,1-a]isoquinoline,
2-(beta-methoxyethyl)-s-triazolo[5,1-a]isoquinoline,
2-ethoxymethyl-s-triazolo[5,1-a]isoquinoline,
2-(2-pyridyl)-s-triazolo[5,1-a]isoquinoline,

and the like.

Another way to prepare substituted s-triazolo[5,1-a]isoquinoline derivatives is to react a readily obtainable s-triazolo[5,1-a]isoquinoline (such as one containing one or more chloro substituents) in accordance with known reactions in order to introduce other substituent groups. The following reactions, wherein R represents an s-triazolo[5,1-a]isoquinolyl group, are illustrative:

wherein R' represents C₂-C₄ alkyl

Among the s-triazolo[5,1-a]isoquinolines that can be produced by the above-exemplified reactions (j) through (z) are the following specific illustrative compounds:

2-methyl-5-dimethylamino-s-triazolo[5,1-a]isoquinoline,
2-trifluoromethyl-9-(3-aminopropylamino)-s-triazolo[5,1-a]isoquinoline,

2-phenyl-6-(2-dimethylaminoethylamino)-s-triazolo[5,1-a]isoquinoline,

2-methyl-5-bromo-s-triazolo[5,1-a]isoquinoline,

2-phenyl-6-bromo-s-triazolo[5,1-a]isoquinoline,

2-trifluoromethyl-9-bromo-s-triazolo[5,1-a]isoquinoline,
2-methyl-5-(2-dimethylaminoethoxy)-s-triazolo[5,1-a]

isoquinoline,
2-methyl-9-cyano-s-triazolo[5,1-a]isoquinoline,

2-trifluoromethyl-6-thiocyanato-s-triazolo[5,1-a]

isoquinoline,
2-methyl-8,9-dichloro-s-triazolo[5,1-a]isoquinoline,
2,5-dimethyl-6-aminoethyl-s-triazolo[5,1-a]isoquinoline,
2-phenyl-7-nitro-s-triazolo[5,1-a]isoquinoline,
2-trifluoromethyl-6-ethylthio-s-triazolo[5,1-a]isoquinoline,

and the like.

The tetrazolo[5,1-a]isoquinolines can be produced from known reactants by known types of reactions. For instance, they can be produced by the following sequence of reactions:

(1) A 1-chloroisoquinoline is reacted with hydrazine to yield a 1-hydrazinoisoquinoline (this reaction is known):

(2) A 1-hydrazinoisoquinoline is reacted with nitrous acid to produce the tetrazolo[5,1-a]isoquinolines of the invention:

Reaction (2) is a known type of reaction, although it had not heretofore been applied to 1-hydrazinoisoquinolines. In the usual case, the nitrous acid is generated in situ from alkali metal nitrite and an acid such as hydrochloric acid. A suitable way to carry out the reaction is to first dissolve the 1-hydrazinoisoquinoline in aqueous inorganic acid, such as hydrochloric acid. It may be necessary to warm the mixture in order to facilitate dissolution. The solution is then cooled in an ice bath to about 50 -15° to +10° C., and an aqueous solution of sodium nitrite is added in about stoichiometric proportions (i.e., about 1 to 1.1 moles of sodium nitrite per mole of 1-hydrazinoisoquinoline). The reaction mixture is then stirred for a short period of time, such as from about 15 to 30 minutes, and the product is recovered by filtration (the tetrazolo[5,1-a]isoquinoline is insoluble in water), and purified by recrystallization from an ethanol/water mixture.

The substituent groups in the tetrazolo[5,1-a]isoquinolines can be introduced by procedures that are known in the art. For instance, many substituted tetrazolo[5,1-a]isoquinolines can be prepared from known 1-chloroisoquinolines that have the same substituent group. Examples of known 1-chloroisoquinolines and the corresponding tetrazolo[5,1-a]isoquinolines produced therefrom include the following compounds:

1,3-dichloroisoquinoline to produce 5-chlorotetrazolo[5,1-a]isoquinoline,

1,4-dichloroisoquinoline to produce 6-chlorotetrazolo[5,1-a]isoquinoline,

When starting with a dichloroisoquinoline, the reaction with hydrazine (i.e., Reaction (1) above) is preferably carried out in methanol, since the 1-hydrazinoisoquinoline, which forms first, is very insoluble in methanol.

Thus, by precipitation of the 1-hydrazino compound, the preparation of dihydrazino derivatives is avoided.

1,4-dichloro-3-methylisoquinoline to produce 6-chloro-5-methyltetrazolo[5,1-a]isoquinoline,
 1-chloro-3-phenylisoquinoline to produce 5-phenyltetrazolo[5,1-a]isoquinoline,
 1,4-dichloro-3-phenylisoquinoline to produce 6-chloro-5-phenyltetrazolo[5,1-a]isoquinoline,
 1,7-dichloroisooquinoline to produce 9-chlorotetrazolo[5,1-a]isoquinoline,
 1,5-dichloroisooquinoline to produce 7-chlorotetrazolo[5,1-a]isoquinoline,
 1-chloro-5-methoxyisoquinoline to produce 7-methoxytetrazolo[5,1-a]isoquinoline,
 1-chloro-6-methoxyisoquinoline to produce 8-methoxytetrazolo[5,1-a]isoquinoline,
 1-chloro-7-methoxyisoquinoline to produce 9-methoxytetrazolo[5,1-a]isoquinoline,
 1-chloro-3-ethylisoquinoline to produce 5-ethyltetrazolo[5,1-a]isoquinoline,
 and the like.

Some known isocarboxylic acids, the 1-chloroisooquinolines derived therefrom by reaction (i) above, and the tetrazolo[5,1-a]isoquinolines produced from the 1-chloroisooquinolines via reactions (1) and (2) above, include the following:

5,6,7-trimethoxyisocarboxylic acid,
 1-chloro-5,6,7-trimethoxyisoquinoline, and
 7,8,9-trimethoxytetrazolo[5,1-a]isoquinoline,
 6,7-dimethoxyisocarboxylic acid,
 1-chloro-6,7-dimethoxyisocarboxylic acid, and
 8,9-dimethoxytetrazolo[5,1-a]isoquinoline,
 3-methyl-4-cyanoisocarboxylic acid,
 1-chloro-3-methyl-4-cyanoisoquinoline, and
 5-methyl-6-cyanotetrazolo[5,1-a]isoquinoline,
 4-carboxyisocarboxylic acid,
 1-chloro-4-carboxyisoquinoline, and
 6-carboxytetrazolo[5,1-a]isoquinoline,

and the like.

Another way to prepare substituted tetrazolo[5,1-a]isoquinoline derivatives is to react a readily obtainable tetrazolo[5,1-a]isoquinoline (such as one containing one or more chloro substituents) in accordance with known reactions in order to introduce other substituent groups. Such known reactions include reactions (j) through (z), above.

In some cases when the halo group is in the 6 position on the tetrazolo[5,1-a]isoquinoline nucleus, the product of a substitution reaction will have the substituent on the 5 position instead of the expected 6 position. For instance, the reaction of 6-chlorotetrazolo[5,1-a]isoquinoline with sodium methoxide in methanol solvent yields 5-methoxytetrazolo[5,1-a]isoquinoline instead of the expected 6-methoxy derivative. However, reaction of the same 6-chloro compound with sodium methanethiolate in dimethyl sulfide solvent produces the expected 6-methylthiotetrazolo[5,1-a]isoquinoline.

From the foregoing discussion, it is seen that the invention can employ a wide variety of tetrazolo[5,1-a]isoquinolines. Included are those compounds that can be prepared directly from readily available 1-hydrazinoisoquinolines such as alkyl-, chloro-, alkoxy-, phenyl-, cyano-, and carbalkoxy - substituted tetrazolo[5,1-a]isoquinolines. These classes of compounds were exemplified by the specific compounds enumerated above. Additional tetrazolo[5,1-a]isoquinolines that are within the scope of the invention are those that can be produced by known types of reactions such as reactions (j) through (z), above. Specific illustrations of such tetrazolo[5,1-a]isoquinolines include the following compounds:

5-methylthiotetrazolo[5,1-a]isoquinoline,
 6-methylthiotetrazolo[5,1-a]isoquinoline,
 6-carboxytetrazolo[5,1-a]isoquinoline,
 5-(N-morpholino)tetrazolo[5,1-a]isoquinoline,

5-(N,N-dimethylamino)tetrazolo[5,1-a]isoquinoline,
 8 - [2 - (N,N - dimethylamino)ethoxy]tetrazolo[5,1-a]isoquinoline,
 7-[3-(N,N-dimethylamino)propylamino]tetrazolo[5,1-a]isoquinoline,
 9-cyanotetrazolo[5,1-a]isoquinoline,
 5-aminoethyltetrazolo[5,1-a]isoquinoline,

and the like.

The preferred tetrazolo[5,1-a]isoquinolines include unsubstituted tetrazolo[5,1-a]isoquinoline and those compounds containing lower alkyl, lower alkoxy, chloro, amino, N,N-diethylamino, lower alkylthio, aminoalkylamino, and aminoalkoxy groups. It is also preferred that the alkyl moieties in said groups contain from 1 to 4 carbon atoms.

The process of the invention selectively hydrogenates the tri- and tetrazoloisoquinolines in the 5,6 position. Broadly, the process comprises contacting the tri- or tetrazoloisoquinoline with hydrogen gas in the presence of a nickel, palladium, or platinum catalyst. The hydrogenation reaction can be conveniently carried out in accordance with the following procedure:

The compound to be hydrogenated is charged to a conventional pressure vessel, such as an autoclave, along with an inert solvent such as ethanol or isopropyl alcohol. A catalytic quantity of the hydrogenation catalyst is then added. Useful catalysts include nickel, palladium, or platinum deposited on charcoal, with palladium-on-charcoal being preferred. Useful catalytic quantities for one mole of the compound to be hydrogenated have been found to be from about 20 to 40 grams of a catalyst consisting of about 5 weight percent nickel, palladium or platinum-on-charcoal. (The weight refers to active metal catalyst plus charcoal, not to active metal catalyst alone.) The autoclave is then flushed with hydrogen, sealed, and hydrogen gas is injected to a pressure of, for instance, over 20 atmospheres and up to 100 atmospheres or more. The autoclave is shaken to saturate the mixture, and additional hydrogen is added to bring the pressure back up. The autoclave is then slowly heated from room temperature at a rate of, for example, about 20° C. per hour, and the pressure increase is plotted against time (or temperature). Before the hydrogenation of the 5,6 position starts, the graph of pressure v. time or temperature will be very close to linear. (Hydrogenation of easily reducible substituents such as nitro will occur first, and such reductions should be completed before plotting the graph). The initiation of the hydrogenation reaction is detected by a somewhat lower rise than that which is extrapolated. When the reaction starts, heating is reduced and the temperature is allowed to increase by about 10° C. and it is then stabilized. At this temperature, the hydrogenation reaction rate will be about 0.01 mole per hour per gram of catalyst ("catalyst" refers to active metal plus charcoal, when metal catalyst deposited on charcoal is used as the catalyst). Reaction rate would increase by a factor of about 2 for a 10° C. rise in temperature.

The hydrogenation reaction is normally carried out at temperatures within the range of from about 50° to 160° C., and preferably from about 80° C. to 110° C. The hydrogenation reaction is followed by observing the pressure decrease. When the pressure stops decreasing, the reaction has stopped.

Under the conditions described above, the hydrogenation is selective for the 5,6 position. Additional hydrogenation on the rings does not become significant until temperature is raised about 50° C. above the temperature at which reaction is first observed.

The hydrogenated product is recovered by standard procedures such as by filtration to separate the catalyst, evaporation of the solvent, and recrystallization from a convenient solvent such as ethanol, butanol, cyclohexane, benzene, ethanol/water, or the like. Yields are usually 80 percent or higher.

From the foregoing description of a convenient way for carrying out the process of the invention, it is seen that the process can be described as follows:

The process comprises reacting a tri- or tetrazoloisoquinoline with hydrogen in the presence of a hydrogenation catalyst at a temperature within the range of from about 50° to about 160° C., and preferably from about 80° to about 110° C., for a period of time sufficient to hydrogenate the 5,6 position of said tri- or tetrazoloisoquinoline, provided that the reaction temperature employed is not more than about 50° C. higher, and preferably not more than 30° C. higher, than the temperature at which the hydrogenation reaction begins.

Among the 5,6-dihydrotetrazolo[5,1-a]isoquinolines that can be produced by the invention are the following compounds:

5,6-dihydrotetrazolo[5,1-a]isoquinoline,
8,9-dimethoxy-5,6-dihydrotetrazolo[5,1-a]isoquinoline,
5-chloro-5,6-dihydrotetrazolo[5,1-a]isoquinoline,
6-chloro-5,6-dihydrotetrazolo[5,1-a]isoquinoline,
9-chloro-5,6-dihydrotetrazolo[5,1-a]isoquinoline,
7-methoxy-5,6-dihydrotetrazolo[5,1-a]isoquinoline,
5-ethyl-5,6-dihydrotetrazolo[5,1-a]isoquinoline,
5-methylthio-5,6-dihydrotetrazolo[5,1-a]isoquinoline,
9-[2-(N,N-dimethylamino)ethoxy]-5,6-dihydrotetrazolo[5,1-a]isoquinoline,

as well as the 5,6-dihydro derivatives of the starting reactants enumerated above.

Among the 5,6-dihydro-s-triazolo[5,1-a]isoquinolines that are provided by the process of the invention are the following specific illustrative compounds:

2-methyl-5,6-dihydro-s-triazolo[5,1-a]isoquinoline,
2-trifluoromethyl-5,6-dihydro-s-triazolo[5,1-a]isoquinoline,
2-phenyl-5,6-dihydro-s-triazolo[5,1-a]isoquinoline,
8,9-dimethoxy-2-methyl-5,6-dihydro-s-triazolo[5,1-a]isoquinoline,
5-chloro-2-trifluoromethyl-5,6-dihydro-s-triazolo[5,1-a]isoquinoline,
6-chloro-2-methyl-5,6-dihydro-s-triazolo[5,1-a]isoquinoline,
9-chloro-2-phenyl-5,6-dihydro-s-triazolo[5,1-a]isoquinoline,
5-methylthio-2-methyl-5,6-dihydro-s-triazolo[5,1-a]isoquinoline,
9-[2-(N,N-dimethylamino)ethoxy]-2-methyl-5,6-dihydro-s-triazolo[5,1-a]isoquinoline,

and the 5,6-dihydro derivatives of each of the starting reactants enumerated above.

Among the 5,6-dihydro-s-triazolo[3,4-a]isoquinolines that can be produced by the process of the invention are the following illustrative compounds:

5,6-dihydro-s-triazolo[3,4-a]isoquinoline,
5,6-dihydro-3-trifluoromethyl-s-triazolo[3,4-a]isoquinoline,
5,6-dihydro-8,9-dimethoxy-s-triazolo[3,4-a]isoquinoline,
5,6-dihydro-3-methyl-s-triazolo[3,4-a]isoquinoline,

as well as the 5,6-dihydro derivatives of each of the starting reactants enumerated above.

The compounds that can be produced by the process of the invention are very useful. Because they are basic in nature, they can be used as hydrogen halide acceptors in processes such as the one disclosed in U.S. Pat. No. 3,071,605 for the production of cyclopentadienyl metal compounds. The compounds can also be used as corrosion inhibitors in aqueous ethylene glycol-based cooling liquids. The compounds that can be produced by the process of the invention which contain active hydrogen atoms can be reacted with ethylene oxide to form surface active agents useful as wetting agents, detergents, and the like. The compounds are also useful as reaction intermediates.

The examples appearing below illustrate the invention.

STANDARDIZED CONDITIONS

In the examples, the following standardized procedure and conditions were used, unless otherwise indicated:

To a 250-milliliter autoclave was charged 0.05 mole of the tri- or tetrazoloisoquinoline to be hydrogenated, 100 milliliters of isopropyl alcohol, and 1.5 grams of 5 weight percent palladium-on-charcoal (Type 16, from Johnson, Matthey & Co. Ltd.). The autoclave was flushed with hydrogen, sealed and filled with hydrogen at room temperature to a pressure of about 80 atmospheres. The autoclave was then shaken in order to saturate the liquid, and additional hydrogen was added to restore the pressure to 80 atmospheres. The autoclave was slowly heated (at a rate of about 20° C. per hour) and the pressure increase was plotted against time. The beginning of the reaction was detected by a somewhat slower pressure rise than that which was extrapolated. The temperature was allowed to increase to about 10° C. higher than the temperature at which the reaction was first detected. The contents of the autoclave were then held at that temperature until the hydrogenation pressure stopped decreasing. The autoclave was then cooled and vented, and the solvent was evaporated after filtering out the catalyst. Purification of the product, if necessary, was done by recrystallization. The following materials were hydrogenated:

Example 1

8,9-dimethoxy-s-triazolo[3,4-a]isoquinoline was hydrogenated to 5,6-dihydro-8,9-dimethoxy-s-triazolo[3,4-a]isoquinoline. The reaction was first detected at 80° C., and was carried out at 90° C. The rate at 90° C. was about $\frac{1}{60}$ mole/hour/gram of catalyst. The yield was close to 100% without recrystallization. Elemental analysis of the product was:

Calculated (percent): C, 62.32; H, 5.67; N, 18.17; O, 13.84. Found (percent): C, 62.11; H, 5.70; N, 17.64; O, 14.43.

Example 2

3-methyl-s-triazolo[3,4-a]isoquinoline was hydrogenated to 5,6-dihydro-3-methyl-s-triazolo[3,4-a]isoquinoline. The reaction was first detected at 85° C., and it was carried out at 90° C. The rate at 90° C. was about 0.01 mole/hour/gram of catalyst. The yield was about 80%. The product was identified by comparison of the infrared spectrum with an authentic sample.

Example 3

s-Triazolo[3,4-a]isoquinoline was hydrogenated to 5,6-dihydro-s-triazolo[3,4-a]isoquinoline. The conditions were analogous to Example 2. Elemental analysis of the product was:

Calculated (percent): C, 70.15; H, 5.30; N, 24.55. Found (percent): C, 69.87; H, 5.29; N, 24.32.

Example 4

3-trifluoromethyl-s-triazolo[3,4-a]isoquinoline was hydrogenated to 5,6-dihydro-3-trifluoromethyl-s-triazolo[3,4-a]isoquinoline by procedure and conditions analogous to Example 2. The elemental analysis of the product was:

Calculated (percent): C, 55.21; H, 3.37; N, 17.56. Found (percent): C, 55.03; H, 3.55; N, 17.27.

Example 5

To a 250 ml. autoclave were charged 10 grams tetrazolo[5,1-a]isoquinoline, 100 milliliters of ethanol, and 1.5 grams of 5 weight percent palladium-on-charcoal (Type 16, from Johnson, Matthey & Co. Ltd.). The autoclave was flushed with hydrogen, sealed and filled with hydrogen at room temperature to about 88 kilograms per cm.² pressure. The autoclave was slowly heated to 100° C. and held there until the hydrogen pressure levelled off. The autoclave was cooled and vented, and the solvent was evaporated. After recrystallization from benzene/cyclohexane, there was obtained 6 grams of 5,6-dihydrotetrazolo[5,1-a]isoquinoline, M.P. 96° C.

15

Example 6

To a 250 ml. autoclave were charged 0.05 mole 2-methyl-s-triazolo[5,1-a]isoquinoline, 100 milliliters of isopropanol, and 1.5 grams of 5 weight percent palladium-on-charcoal (Type 16, from Johnson, Matthey & Co. Ltd.). The autoclave was flushed with hydrogen, sealed and filled with hydrogen at room temperature to about 88 kilograms per cm.² pressure. The autoclave was slowly heated to 90° C. and held there until the hydrogen pressure levelled off. Reaction rate at 90° C. was $\frac{1}{50}$ mole/hour/gram of catalyst. The autoclave was cooled and vented, and the solvent was evaporated. After recrystallization from benzene/cyclohexane, there was obtained 2-methyl-5,6-dihydro-s-triazolo[5,1-a]isoquinoline. M.P. 54-56° C. in 80 percent yield.

Elemental analysis: Calculated (percent): C, 71.33; H, 5.99; N, 22.69. Found (percent): C, 71.44; H, 6.12; N, 22.83.

What is claimed is:

1. The process of preparing 5,6-dihydro-3-trifluoromethyl-s-triazolo[3,4-a]isoquinoline by reacting hydrogen with 3-trifluoromethyl-s-triazolo[3,4-a]isoquinoline at a

16

temperature within the range of from about 50° to about 160° C. and at a pressure of from about 20 to about 100 atmospheres in the presence of a catalytic quantity of a platinum or palladium hydrogenation catalyst for a period of time sufficient to hydrogenate the 5,6 position of said 3-trifluoromethyl-s-triazolo[3,4-a]-isoquinoline.
